(57) **CLAIM**

The ornamental design for a vegetable cutter, as shown and described.

DESCRIPTION

FIG. 1 is a front perspective view of a vegetable cutter, showing my new design;

FIG. 2 is a rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is a perspective view of the vegetable cutter from FIG. 1 shown with environmental structure;

FIG. 10 is a front perspective view of another embodiment;

FIG. 11 is a rear perspective view of another embodiment;

FIG. 12 is a front view of another embodiment;

FIG. 13 is a rear view of another embodiment;

FIG. 14 is a left side view of another embodiment;

FIG. 15 is a right side view of another embodiment;

FIG. 16 is a top view of another embodiment;

FIG. 17 is a bottom view of another embodiment;

FIG. 18 is a perspective view of the vegetable cutter from FIG. 10 shown with environmental structure;

FIG. 19 is an enlarged detail view of area 19 in FIG. 2; and,

FIG. 20 is an enlarged detail view of area 20 in FIG. 11.

The broken lines in the drawings illustrate environmental structure that form no part of the claimed design.

The dash-dot-dash broken lines encircling the enlarged views are for annotative purposes only and form no part of the claim thereof.

1 Claim, 20 Drawing Sheets
